UNITED STATES PATENT OFFICE.

JAMES R. BALL AND WILLIAM H. BALL, OF CHICAGO, ILLINOIS; SAID WILLIAM H. BALL ASSIGNOR TO SAID JAMES R. BALL.

CREASING DEVICE FOR TROUSERS.

Application filed March 18, 1922. Serial No. 544,917.

To all whom it may concern:

Be it known that we, JAMES R. BALL and WILLIAM H. BALL, citizens of the United States, and residents of the city of Chicago, county of Cook, and State of Illinois, have invented certain new and useful Improvements in Creasing Devices for Trousers, of which the following is a specification.

This invention relates to creasing devices for trousers, and has for its object the provision of a device adapted to be disposed in a leg of a pair of trousers and expanded to stretch the trouser leg thereover to crease same.

Another object of the invention is to provide such a device with several independently movable, and independently adjustable frames, such arrangement being for the purpose of permitting conformation of said frames to variously shaped trouser legs, in order to insure that stretching of the trouser leg will be uniform at all points along same, no matter what the shape of the trouser leg.

Still another object of the invention is to provide means whereby the upper portion of the trouser leg may be stretched and then the lower portion of such trouser leg pulled longitudinally along the device so as to stretch the baggy portion ordinarily present in unpressed trousers, and then subsequently securing said stretched portion on the device by an independent adjustment thereof, thus securing the trouser leg in stretched position, at the same time creasing same.

Still another object of the invention is to provide means whereby the device may be longitudinally collapsed and laterally folded into small size, said means also being operative to permit lateral folding of the device while same is in operative position with a trouser leg stretched thereover, thus permitting the device to be inserted into a trouser leg and then folded laterally so as to occupy but approximately half its original size, the device in such position of course being of a size which may be placed in a suit case or other similar receptacle.

Other objects will appear hereinafter.

The invention consists in the combinations and arrangements of parts hereinafter described and claimed.

The invention will be best understood by reference to the accompanying drawings forming a part of this specification, and in which,

Fig. 1 is an elevation of the invention showing same in completely folded position;

Fig. 2 is an elevation of the invention in partially unfolded position;

Fig. 3 is a view of the invention in operative position;

Fig. 4 is a sectional view on the line 4—4 of Fig. 3;

Fig. 5 is a detail view of a slidable bracket used in connection with the invention;

Fig. 6 is a view of the invention applied to a trouser leg showing same in partially adjusted position;

Fig. 7 is a similar view of the invention showing same in fully adjusted position;

Fig. 8 is a fragmentary view of the guide member used in connection with the invention, showing means adapted to compensate for adjustable movements of the device; and

Fig. 9 is a fragmentary view of an attachment to be used in connection with the invention.

The invention comprises a main frame and an auxiliary frame hingedly connected together, said frames being adapted to be inserted into a trouser leg and independently adjusted in operative position. The main frame consists of oppositely disposed bars 10 and 11 of any suitable material, such as sheet metal. Each of the bars 10 and 11 consists of a piece of material folded onto itself as shown at 12, and having its edges 13 again folded inwardly as clearly shown in Fig. 4 of the drawings. The folds 12 thus provided form sharp edges for the bars which are particularly efficacious in imparting a crease to the trouser leg. The material frame from which the bars 10 and 11 are formed is preferably galvanized iron, or other suitable non-corrosive sheet metal,

such metal being employed for the reason

that same may be moistened when the device is used so as to aid in imparting a crease to the trouser leg.

The lower ends of the bars 10 and 11 are 5 movably connected together by means of a pair of links 14, said links preferably having their outer ends pivotally mounted between the edges 13 of the bars 10 and 11 by suitable pins or rivets 15, as shown in Figs. 3 and 10 4. The inner ends of such links are preferably pivotally connected by any suitable means to the end of an operating rod 16, which rod is slidably mounted at its upper end in a bracket 17. The bracket 17 may 15 be a casting of the type shown in Fig. 5 having an opening 18 therein adapted to slidably engage the operating rod 16. Such bracket is also preferably provided with 20 forked ends 19 adapted to have pivotally mounted therein the inner ends of links 20, the outer ends of such links being pivotally held between the edges 13 of the bars 10 and 11 by pins or rivets 21, in the same manner 25 as the ends of the links 14. A set screw 22 is tapped into the casting 17 as shown in Fig. 5 for the purpose of adjustably regulating the sliding movement of the rod 16, and the space between the bars 10 and 11. In order to prevent undesirable longitudinal 30 movement of the bars 10 and 11 with respect to each other, we provide a pair of links 25 and 26, which are preferably oppositely disposed to the links 14. The outer ends of the links 25 and 26 are pivotally held between 35 the edges 13 of the bars 10 and 11 preferably adjacent the outer ends of the links 14, by rivets 27. The inner end of the link 25 is pivotally connected to a guide member 28 slidably mounted on the rod 16. The link 26 has its inner end slidably mounted 40 in a slot 29 provided in the guide member 28. By this arrangement it will be seen that the lower end of the bar 11 may approach the rod 16 more closely than the 45 lower end of the bar 10, this construction being for the purpose of permitting adaptation of the device to the upper leg and seat of trouser legs of various sizes. The lower end of the bar 11 is preferably 50 bevelled as shown at 29', this being for the purpose of permitting angular movement with respect to the auxiliary frame of the device as will be hereinafter explained.

The auxiliary frame of the device consists 55 of oppositely disposed bars 30 and 31 similar in all respects to the bars 10 and 11, except for the bevelled end of the bar 11.

The inner end of the bar 30 is connected 60 by a hinge 32 with the bar 10. The hinges 65 32 may be of any suitable construction but we preferably employ a hinge which has one end rigidly secured between the edges 13 of the bar 10 at the end thereof by means of rivets 33, the opposite end of said hinge being pivotally secured between the edges of the

end of the bar 30 by a rivet 34. This construction provides for inward swinging of the member 30 in the plane of the frame. Outward swinging of the member 30 beyond a straight line formed with the bar 10 is prevented because the pivot 34 of the hinge 32 is adjacent the inner edge of the bar 30 and the outer adjacent edges of the bars 10 and 30 abut against each other.

The adjacent ends of the bars 11 and 31 are connected together in precisely the same manner as the bars 10 and 30, and similar reference characters are used to designate the parts of both connections. In this connection it will be seen that the bevelled edge 29' of the bar 11 while forming a joint in the same manner as the adjacent outer edges of the bars 10 and 11, permits a greater latitude of movement, to permit conformation of the bar 11 to the upper leg and seat of the trousers without disturbing the alignment of the bar 31. It will be noted from the above description of the hinge connection between the bars 10 and 11 and 30 and 31 that the latter bars are movable 90 inwardly in the plane of the frame, and laterally foldable upon the bars 10 and 11.

The bars 30 and 31 are adjustably connected together at their lower ends by means of a pair of links 35 having their outer ends pivotally secured between the edges of the bars 30 and 31, the inner ends of said links being connected by a suitable set screw 36, adjustment of said links determining the 95 space between the bars 30 and 31.

In operation the device is inserted into the upper end of the trouser leg a suitable distance and expanded, and by reason of the arrangement of the links 14, 20, 25, and 26, the bar 11 is free to adjust itself to the upper leg and seat of the trousers. When the members have been expanded the desired distance the set screw 22 is screwed home retaining such members in adjusted position. The bars 30 and 31 are still free to move in the plane of the frame, so that the lower leg of the trousers may be pulled down to stretch the baggy portion thereof, and then the bars 30 and 31 expanded by means of the links 35, such links then being set in 110 position by tightening the set screw 36. After leaving the frame in position in the trouser leg a suitable time, same can be removed and applied to the other trouser leg as described, and when there is no further use for the device, same may be folded into 115 small size as shown in Fig. 1.

In Fig. 9 is shown an attachment which is 120 adapted for use when the form of a trouser leg is bell shaped. This consists of a folded 125 wedge-shaped piece of material 40 similar to that from which the frames are made, adapted to be disposed over the lower end of the bar 41, the wider end of such wedged portion being provided with apertures 42, in 130

which a suitable pin (not shown) may be selectively inserted and adapted to ride on the edge of the bar 41. The wedge-shaped portion 40 is adapted to be slid along the bar 41 to stretch the form of the trouser leg as shown in Fig. 9.

While we have illustrated and described the preferred form of construction for carrying our invention into effect, this is capable of variation and modification without departing from the spirit of the invention. We, therefore, do not wish to be limited to the precise details of the construction set forth, but desire to avail ourselves of such variations and modifications as come within the scope of the appended claims.

Having described our invention, what we claim as new and desire to secure by Letters Patent is:

1. A trouser creasing device of the character described comprising a main frame having side bars operatively connected together; means for expanding said side bars to relatively spaced positions; means for rigidly holding said bars against angular displacement with respect to each other; an auxiliary frame having side bars movably connected to the side bars of said main frame; and means for adjusting the angular relation of the side bars of said auxiliary frame independently of the angular adjustment of the side bars of said main frame.

2. A trouser creasing device of the character described comprising a main frame having side bars operatively connected together; means for expanding said bars to relatively spaced positions; means to permit angular variation between the positions of said bars; means for rigidly holding said bars against angular displacement; an auxiliary frame having side bars movably connected to the side bars of said main frame; and means for adjusting the angular relation between the side bars of said auxiliary frame independently of the angular adjustments of the side bars of said main frame.

3. In a trouser creasing device comprising a frame having side bars; oppositely disposed sets of links pivotally-connected to said side bars; an operating rod having its inner end pivotally connected to the inner ends of one set of links and slidably engaging the opposite set of links; a guide member slidably mounted on said operating rod and having a slot therein; a link pivotally connected to one of said bars and having its opposite end pivotally connected to said guide member; and a link having its outer end pivotally connected to the other of said bars and having its inner end slidably and pivotally mounted in said slot.

4. In a trouser creasing device having side bars; oppositely disposed sets of links pivotally connected to said side bars, an operating rod pivotally connected to the

inner ends of one set of links and slidably engaging the opposite sets of links, outward movement of said operating rod being adapted to separate said bars; an auxiliary frame operatively connected to said first named frame; and means for independently adjusting said second named frame.

5. In a trouser creasing device comprising a frame having side bars; oppositely disposed sets of links pivotally connected to said side bars; an operating rod having its inner end pivotally connected to the inner ends of one set of links and slidably engaging the opposite set of links; a guide member slidably mounted on said operating rod and having a slot therein; a link pivotally connected to one of said bars and having its opposite end pivotally connected to said guide member; a link having its outer end pivotally connected to the other of said bars and having its inner end slidably and pivotally mounted in said slot; an auxiliary frame operatively connected to said first named frame; and means for independently adjusting said second named frame.

6. In a trouser creasing device comprising a frame having side bars; oppositely disposed sets of links pivotally connected to said side bars; an operating rod having its inner end pivotally connected to the inner ends of one set of links and slidably engaging the opposite set of links; a guide member slidably mounted on said operating rod and having a slot therein; a link pivotally connected to one of said bars and having its opposite end pivotally connected to said guide member; a link having its outer end pivotally connected to the other of said bars and having its inner end slidably and pivotally mounted in said slot; an auxiliary frame operatively connected to said first named frame; means for independently adjusting said second named frame; a wedged shaped portion slidably mounted on the lower end of one of said bars; and means for adjusting the depth of said wedged portion.

7. In a trouser creasing device having side bars, oppositely disposed sets of links pivotally connected to said side bars; an operating rod pivotally connected to the ends of one set of links and slidably engaging the opposite sets of links; means for preventing longitudinal movement of said bars with respect to each other; means for permitting variation in the angular positions of said bars; an auxiliary frame connected to said bars; and means for independently adjusting said auxiliary frame.

8. A trouser creasing device of the character described comprising a main frame having side bars operatively connected together; means for expanding said bars to relatively spaced positions; means for rigidly holding said bars against angular displacement; an auxiliary frame having side

bars; hinge members pivotally connecting the ends of the main frame, and the ends of said auxilliary frame, each of said hinge members having one side rigidly connected to one of said ends, and the other side pivotally connected to another of said ends, whereby the bars of said main and auxiliary frames are pivotally mounted to swing in the plane of the frame, and being laterally foldable; and means for adjusting the angular relation of the side bars of said auxil-

iary frame independently of the angular adjustment of the side bars of said main frame.

In testimony whereof we have signed our ¹⁵ names to this specification in the presence of two subscribing witnesses.
